ABSTRACT

A toy which includes a plurality of FIGS. simulating living creatures and an enclosure simulating a house for these creatures. The figures which simulate the living creatures may represent different animals, birds and the like. The enclosure, which may simulate a barn, for example, has a plurality of door-simulating bodies movable between open and closed positions, and these bodies respectively carry locks provided with key-receiving portions of different configurations. The several figures which represent the various creatures are respectively provided with keys of different configurations to be respectively received in the key-receiving portions of the locks, so that only a figure representing a given creature will be able to lock and unlock a given door-simulating body. The keys which are carried by the several figures are characteristic of different parts of the anatomy of the figures such as the snouts of four-legged creatures or the bills of birds.

TOY SIMULATING LIVING CREATURES AND AN ENCLOSURE THEREFOR

BACKGROUND OF THE INVENTION

The present invention relates to toys.

In particular, the present invention relates to toys of the type which include toy figures which simulate various living creatures such as different animals or birds, and an enclosure which simulates a house in which the creatures live.

There are known toys of this general type where an enclosure simulating a house for given creatures is adapted to accommodate figures which represent the creatures. However, conventional toys of this type do not challenge the intelligence of children. When children play with toys of conventional construction, the children soon become bored because there is no sustained entertainment value in such toys. Such conventional toys do not present to the children any problems which they must solve and the entertainment and attention-sustaining value of such conventional toys are undesirably deficient.

SUMMARY OF THE INVENTION

It is accordingly a primary object of the present invention to provide a toy of the above general type which will have a high level of entertainment and attention-sustaining capability.

Also, it is an object of the present invention to provide a toy of this general type which will teach children valuable concepts such as the placing of different items in their proper locations and the matching together of pairs of items of similar configurations and sizes.

It is also an object of the present invention to provide a toy which will achieve these objects without requiring the structures of the toy to depart from structures which are representative of shapes which are actually encountered.

Furthermore, it is an object of the invention to provide a toy which is simple and inexpensive and which at the same time can be used with complete safety by young children.

According to the invention, the toy includes an enclosure which simulates a house for living creatures such as animals and birds. The enclosure has a wall formed with openings through which figures which simulate the living creatures can be introduced into and removed from the interior of the enclosure. A plurality of door-simulating bodies are operatively connected to the enclosure at the wall openings thereof for movement between closed positions closing the openings and open positions permitting movement of the figures through the openings into and out of the enclosure. Each of the door-simulating bodies is provided with a lock means for releasably locking the body in its closed position, and the several lock means are respectively provided with key-receiving portions of different configurations. A plurality of figures which respectively simulate the several creatures are respectively provided with keys of different configurations which match those of the key-receiving portions of the lock means, respectively, so that each figure will be able to operate only one lock means so as to be capable of locking and unlocking only one door-simulating body. The keys of the several figures respectively form characteristic parts of the anatomies thereof.

BRIEF DESCRIPTION OF DRAWINGS

The invention is illustrated by way of example in the accompanying drawings which form part of this application and in which:

FIG. 1 is an elevation of an enclosure forming part of the toy of the invention;

FIG. 2 is a perspective view of one of the several figures of the toy of the invention, the particular figure of FIG. 2 simulating a pig;

FIG. 3 is an end elevation of the enclosure of FIG. 1 as seen from the left of FIG. 1, with one of the door-simulating bodies of the enclosure being shown in its open position in FIG. 3;

FIG. 4 is a fragmentary sectional plan view taken along line 4-4 of FIG. 1 in the direction of the arrows and showing at a scale which is enlarged as compared to FIG. 1 details of a door-simulating body and lock means of the invention;

FIG. 5 is a fragmentary front elevation of the structure of FIG. 4 taken in the direction of line 5-5 of FIG. 4 in the direction of the arrows; and

FIG. 6 is partly sectional fragmentary elevation taken along line 6-6 of FIG. 4 in the direction of the arrows and showing further details of the lock means.

DESCRIPTION OF PREFERRED EMBODIMENTS

Referring to FIG. 1, there is illustrated therein an enclosure 10 which simulates a house for accommodating in its interior various creatures such as different animals and birds. The enclosure 10 may be provided at its top with a handle 12 enabling the enclosure to be carried about to any desired location. The enclosure 10 has a floor 14 and side walls extending upwardly from the floor and joining a roof so that the entire enclosure 10 simulates a barn, as illustrated in FIG. 1.

The enclosure wall 16 which is visible in FIG. 1 is formed with a plurality of openings 18 through which figures which represent various creatures may be introduced into and removed from the interior of the enclosure 10. At the wall 16 the openings 18 are surrounded by flanges 20 which simulate door frames.

A plurality of door-simulating bodies 22 are operatively connected to the enclosure wall 16 at the openings 18 thereof for movement between the closed positions illustrated in FIG. 1, where the bodies 22 prevent figures from being moved into or out of the enclosure, and the open position illustrated for one of the bodies 22 in FIG. 3, permitting figures to be freely moved into and out of the enclosure 10 through the openings 18 thereof.

In the illustrated example the several door-simulating bodies 22 are in the form of rectangular plates provided at their upper and lower right corners, as viewed in FIG. 1, with pins 24 (FIG. 4) received in suitable openings in the floor 14 and in the wall 16 along the upper part of each opening 18, so that each door-simulating body 22 can be swung from the closed position as shown in FIG. 1 to the open position shown for the body 22 at the lower right of FIG. 3.

As is illustrated in FIG. 4, the wall 16 carries next to the floor 14 a transverse bar 26 simulating a threshold and limiting the inward movement of each door-simulating body, so that these bodies 22 can only swing outwardly to their open positions and inwardly to their closed positions. To facilitate swinging of the door-simulating bodies 22 the latter respectively carry handles 28.

In order to maintain the several door-simulating bodies 22 in their closed positions, they are respectively provided with lock means 30, the details of which are illustrated in FIGS. 3-6. Each lock means 30 includes a rotary lock member 32 having a front projecting portion turnably received in an opening 34 of each plate which forms the door-simulating body 22. This front projection fills the opening 34 while being freely turnable therein. Next to the inner surface 36 of each door-simulating body 22, the rotary lock member 32 has an outwardly directed circular flange portion 38 which prevents the rotary lock member 32 from moving forwardly through the opening 34, and this flange 38 has at one portion a radial projection 40 of substantially rectangular configuration adapted to overlap an inner surface portion of the enclosure wall 16 to prevent opening of the door-simulating body 22. Each rotary lock member 32 also has a rearwardly extending circular portion 42 received with a relatively close fit in a circular opening 44 of a wall 44 most clearly shown in FIG. 3 at the inner surface 36 of the door-simulating body 22 which is visible in FIG. 3. This wall 44 has a forwardly extending peripheral flange 46 which directly engages the surface 36 and which spaces the wall 44 from the surface 36 by a distance approximately equal to the thickness of the flange 38 and the lock projection 40. The wall 44 is fixed in any suitable way to the door-simulating body 22 so that it serves to retain the rotary lock member 32 on the door-simulating body. The flange 46 is formed along the free edge 48 of the door-simulating body 22 with an elongated interruption 50 most clearly shown in FIG. 6. This inter-

ruption 50 forms an elongated slot through which the lock projection 40 can freely turn between the position shown in FIG. 5, where the body 22 is maintained closed and the position shown in FIG. 6 where the lock means has been turned to its open position enabling the door-simulating body to be swung to the open position shown for the lower right hand door-simulating body 22 of FIG. 3.

In accordance with a particular feature of the present invention, the several rotary lock means 30 are respectively formed with key-receiving portions 52, and the several key-receiving portions 52 are all of different configurations, as is apparent from FIG. 1.

The toy of invention includes a plurality of figures which simulate various living creatures such as animals or birds. Thus, FIG. 2 shows a figure 54 which simulates a pig. The several door-simulating bodies 22 carry at their exterior surface representations of the several figures. Thus, FIG. 1 shows representations not only of the pig which is simulated by the figure 54 but also of a horse, a goat and a duck. The several figures 54 are respectively provided with keys 56 the configurations of which match those of the differently shaped key-receiving portions 52. These keys 56 which are respectively carried by the several figures respectively form characteristic parts of the anatomy of the animals represented by the figures. Thus, in the case of the figure 54, the key 56 represents the snout of the pig. Thus, it will be seen that the key 56 has substantially an inverted U-shaped configuration, which is characteristic of the snout of a pig. The door-simulating body 22 which carries the representation of a pig thereon is provided at its lock means with a key-receiving portion 52 which matches the configuration of the key 56. This key-receiving illustrated in the opening 52. 52 is in the form of an opening which passes through the front wall of the rotary lock member 32 at the part thereof which is received in the opening 34. Thus, a child using the toy will be compelled to insert the snout 56 of the figure 54 in the opening 52 in order to unlock the proper door-simulating body 22. In order to turn the lock means 30 from the locked position thereof shown in FIGS. 4 and 5, the child will introduce the snout 56 of the figure 54 into the opening 52 and will then turn the lock means to the position shown in FIG. 6 where the snout 56 is means Once the lock means has been turned to the unlocking position of FIG. 6 the figure 54 can be removed and the door can be swung to the open position shown in FIG. 3 where the inner surface 36 of the door-simulating body 22 is shown.

In the same way, the right door of FIG. 1 will be provided at its lock means with a key-receiving portion 52 in the form of an opening of an elongated substantially vertically extending elliptical configuration simulating the snout of a goat, and thus a figure representing a goat will be provided at its snout with a key having a matching configuration enabling the right door of FIG. 1 to be opened and closed. The next door of FIG. 1 has an elongated horizontal key-receiving portion 52 provided with substantially V-shaped ends simulating the configuration of the snout of a horse and thus the figure representing a horse will be provided with a key whose snout matches this configuration enabling this particular door to be opened and closed.

The left door-simulating body 22 of FIG. 1 carries the representation of a duck. The key-receiving portion 52 of the lock means thereof has the configuration of a horizontally extending slot matching the configuration of the front tip of the bill of the duck, so that a figure representing the duck can have the tip of the bill thereof introduced into the key-receiving portion 52 of the left body 22 of FIG. 1 enabling this body to be swung between its open and closed positions.

As is apparent from FIG. 3, the interior of the enclosure 10 can be provided with partitions 58 defining internal compartments for respectively receiving the various figures, and the doors can be provided both at the right and left sides of the enclosure 10, as viewed in FIG. 3.

The entire structure can be made of any suitable material such as wood, plastic, metal, cardboard or other solids, and these materials can be attractively colored for increasing the entertainment and educational value of the toy.

5. What is claimed is:

1. A toy comprising an enclosure having a configuration simulating a house which receives in its interior simulated living creatures such as animals, birds and the like, said enclosure having a wall formed with openings through which figures 10 simulating the living creatures may be introduced into and removed from the enclosure, a plurality of door-simulating bodies operatively connected to said enclosure at said wall openings thereof, respectively, for movement between closed positions preventing movement of figures through said 15 openings and open positions permitting movement of figures through said openings, a plurality of lock means respectively carried by said door-simulating bodies for releasably locking the latter in said closed positions thereof, respectively, said lock means respectively having key-receiving portions of different configurations, respectively, and a plurality of toy figures respectively simulating said creatures and respectively provided with keys respectively having configurations matching those of said key-receiving portions of said plurality of lock means, so that each door can be opened only by a 20 figure provided with a key whose configuration matches that of the key-receiving portion of the lock means of each door.
2. The combination of claim 1 and wherein said keys respectively have configurations which are respectively characteristic of parts of the anatomy of the several figures.
3. The combination of claim 2 and wherein at least one of said figures represents an animal having a snout the configuration of which is characteristic of said animal, and said figure having a snout portion forming said key, one of said lock means having a key-receiving portion whose configuration 25 matches the configuration of said snout portion.
4. The combination of claim 2 and wherein said figure simulates a bird having a bill, and the key-receiving portion of at least one of said lock means having a configuration matching that of said bill to receive the latter, said bill thus forming the 30 key of the latter figure.
5. The combination of claim 1 and wherein said enclosure simulates a barn.
6. The combination of claim 1 and wherein said door-simulating bodies are operatively connected to said enclosure wall 35 for swingable movement with respect thereto between said closed and open positions.
7. The combination of claim 6 and wherein said enclosure wall carries a means for limiting inward movement of said bodies when the latter are in their closed positions so that said door-simulating bodies swing outwardly to said open positions 40 thereof.
8. The combination of claim 7 and wherein said plurality of lock means are respectively in the form of turnable lock members carried by said door-simulating bodies for turning movement with respect thereto, and said lock members respectively overlapping inner surface portions of said enclosure wall when maintaining said door-simulating bodies closed and said lock members being turnable to release positions where they are in a nonoverlapping relationship with respect to the inner surface 45 of said enclosure wall.
9. The combination of claim 8 and wherein said key-receiving portions are respectively in the form of openings passing through said lock members and respectively having said different configurations.
10. The combination of claim 1 and wherein said door-simulating bodies respectively carry at exterior surfaces thereof which are visible when said bodies are in their closed positions representations of the creatures which are respectively provided with the keys to be received at the key-receiving 50 portions of said plurality of lock means, respectively.
